(57) **CLAIM**

The ornamental design for a dual light channel, as shown and described.

DESCRIPTION

FIG. 1 is an isolated perspective view of a dual light channel, showing the new design;

FIG. 2 is a front elevational view of dual light channel thereof;

FIG. 3 is a rear elevational view of the dual light channel thereof;

FIG. 4 is a left side elevational view of the dual light channel thereof;

FIG. 5 is a right side elevational view of the dual light channel thereof;

FIG. 6 is a top plan view of the dual light channel thereof;

FIG. 7 is a bottom plan view of the dual light channel thereof; and,

FIG. 8 is another perspective view of the dual light channel shown in a position of use thereof.

The broken lines in FIG. 8 illustrate portions of the environment of the dual light channel which form no part of the claimed design.
